UNITED STATES PATENT OFFICE.

JOSEPH W. MASON, OF CLEVELAND, OHIO, ASSIGNOR TO THE HART & COMPANY, OF CLEVELAND, OHIO, A CORPORATION OF OHIO.

DESIGN FOR A HAT-LINING.

59,023.

Specification for Design.

Patented Sept. 13, 1921.

Application filed March 21, 1921. Serial No. 454,291. Term of patent 14 years.

To all whom it may concern:

Be it known that I, JOSEPH W. MASON, a citizen of the United States, residing in Cleveland, in the county of Cuyahoga and State of Ohio, have invented a new, original, and ornamental Design for Hat-Linings, of which the following is a specification, reference being had to the accompanying drawing, forming part thereof.

The figure is a bottom plan view of a hat equipped with my new and ornamental

lining, in which 1 represents the border of the hat; and 2 and 3 represent, respectively, the crown tip and the crown lining, forming my new and ornamental lining.

I claim:

The ornamental design for a hat lining, substantially as shown and described.

Signed by me, this 3d day of March, 1921.

JOSEPH W. MASON.
